UNITED STATES PATENT OFFICE.

JOHN REID, OF YONKERS, ASSIGNOR TO THE J. L. MOTT IRON WORKS, OF NEW YORK, N. Y.

COMBINED PLUNGER, NEEDLE, SPRAY, AND SHOWER BATH.

SPECIFICATION forming part of Letters Patent No. 430,253, dated June 17, 1890.

Application filed November 18, 1889. Serial No. 330,731. (No model.)

To all whom it may concern:

Be it known that I, JOHN REID, a citizen of the United States, residing at Yonkers, in the county of Westchester and State of New York, have invented an Improvement in Combined Plunge, Needle, Spray, and Shower Baths, of which the following is a specification.

This improvement is to meet the sanitary demands for bath-room fixtures that are open to and accessible in all parts and separate from the walls of the room or any inclosures, and by my improvements the luxury of a first-class bathing establishment with the plunge, needle, and spray baths is brought into compact form and adapted to private houses. At one end of a plunge bath-tub an upright frame of tubes is provided, having supply-pipes and cocks that admit water into the perforated tubes forming the spray or needle bath, or to the shower-bath at the upper part of the frame, and there is a ring for a hanging curtain, preferably of water-proof material, the lower edge of which passes into the bath-tub, so that the water will all run back into the bath-tub without being scattered upon the floor.

In the drawings, Figure 1 is a perspective view of the bath-tub and attachment complete, and Fig. 2 is a vertical section at one end of the bath-tub through the rising pipe.

The bath-tub P is of any desired character, preferably of metal and porcelain inlined, and the hot-water pipe at the outside of the bath connects with a pipe A within the bath by a coupling-and-ball connection, and the cold-water-supply pipe is similarly connected to the pipe B within the bath-tub, and these pipes rise to a suitable height and are provided with cocks A' B' at the junction of the hot and cold water pipes with the central chamber or mixing-column C, and below this chamber C is a cock D and pipe D', the latter extending down into the bath and terminating with an open muzzle, there being by preference a coupling surrounding the pipe and bolted to the bath-tub to hold the lower end of this pipe D' firmly in position. By means of the cock D hot or cold water, or a mixture at any temperature, can be discharged through the nozzle G into the bath-tub

whenever required, and the cocks A', B', and D are easy of access by a person either outside or inside the bath-tub. The tubular columns H² and H³ are connected at their lower ends by balls and screw-bolts to the bath-tub, and they rise vertically from within the same to the ring M, which firmly connects the upper ends together, and this ring M is also connected to the column H', that rises above the chamber C, there being a cock E intervening between such chamber and the column H'. The columns H² H³ are closed at their upper ends, and the ring M is connected in suitable couplings or joints both to the columns H² and H³ and to the columns H'; but the column H' is continued above the ring M and provided with an arm J', at the end of which is a shower J, of any suitable construction, and the same is central, or nearly so, above the ring M, and there is a valve or cock at F, preferably actuated by a chain and ring F', and the rising column H' is stopped off at L and water is admitted into such column above the plug L through the pipe K, which is at the back of the column H' and extends from the chamber C to the upper part of the column H' above the plug L; hence water is allowed to pass by this pipe K to the shower independently of the valve E in the rising column H'. 80

Connected with and opening into the column H', slightly above the cock E, are the curved pipes I, which extend around and are coupled to the columns H² and H³, and these curved pipes I, together with the similar pipes I' and I², open into such columns H² and H³, and these curved pipes I I' I² and the columns H² and H³ are perforated with ranges of fine holes, and the ends of the curved pipes I' I² are connected by suitable coupling with the pipe D' and column H', respectively; but the curved pipes I' do not open into the pipe D'. It will now be apparent that when the cock E is opened the water will pass into the column H', and by the curved pipes I I² will pass into the columns H² and H³, and thence into the curved pipes I', and the fine jets forming the needle-bath will pass through the perforations in the curved pipes I I' I² and the columns H² H³, and the quantity of water issuing in 95 100

these needle-jets can be regulated by the cock E, and the temperature can be determined by the cocks A' B'. It will now be apparent that by the cocks A' B' the temperature of the water in any part of the apparatus can be regulated. By the cock D the discharge of the water into the bath P can be determined, and by the cock E the needle-bath can be regulated, and by the cock or valve F water can be admitted to the shower when desired, and all the parts of the apparatus are open and easily accessible, so that they can be kept clean, and when manufactured of brass or similar metal the whole apparatus becomes ornamental and acceptable in appearance.

I provide a curtain R of suitable material—such as rubber cloth—and the same is suspended from rings around the circular ring M, and this curtain can be of a length so that its lower end hangs within the upper part of the bath-tub P, and the curtain can be drawn around the bathing apparatus or pushed back to a greater or less extent, as desired, either when the bath is in use or when it is out of use.

By my improvements the bath-tub is availed of as a support for all the pipes. No rigid case or inclosure is used. The pipes are all open and accessible. The vertical pipes or columns connected to the tub support the perforated segmental spray-pipes, and also the curtain-hoop and curtain and the shower. The cocks are easy of access to a person in the bath-tub or outside of the same, and the curtain can be pushed back out of the way when the spray or shower is not in use, and the whole apparatus is accessible and easily kept clean.

I do not claim any of the separate parts of the apparatus, as these have before been used.

I claim as my invention—

1. The combination, with the bath-tub and the hot and cold water supply pipes A and B and cocks A' B', with connections passing through the tub, of the mixing-chamber C, the cock E, rising column H', curved perfo-

rated pipes connected with the rising column, and the columns H² and H³ at the ends of the curved pipes and connected at their lower ends to the bath-tub, substantially as set forth.

2. The combination, with the bath-tub and the hot and cold water supply pipes, of the columns H² H³, connected at their lower ends to the bath-tub, the curved perforated pipes extending from said columns, the rising pipe H' and means for showering, and the cocks connected with the said pipes, substantially as set forth.

3. The combination, with a bath-tub, of columns connected with and rising from the bath-tub, the perforated pipes for the needle-bath supported by said columns, a shower-bath, and the supply-pipes and cocks, substantially as set forth.

4. The combination, with the bath-tub, of columns connected at their lower ends with the bath-tub, curved perforated pipes connecting such columns, the hot and cold water supply pipes and cocks, a mixing chamber with which the hot and cold water supply-pipes are connected, a pipe and cock leading downwardly from the mixing-chamber into the bath-tub, a shower-bath, and pipe and cock leading from the mixing-chamber up to the same, substantially as set forth.

5. The combination, with the bath-tub, of columns connected at their lower ends with the bath-tub, curved perforated pipes connected with the columns and forming the needle-bath, hot and cold water supply pipes and cocks and a mixing-chamber, a pipe and cock leading from the mixing-chamber to the curved perforated pipes, a shower-bath, a pipe leading from the mixing-chamber up to the shower-bath, and a cock or valve to the same, substantially as set forth.

Signed by me this 14th day of November, 1889.

JOHN REID.
